KNITTING FINGER RING

Hymen Greenstein, Brooklyn, N. Y.

Application May 23, 1947, Serial No. 749,993

9 Claims. (Cl. 242—149)

1

The present invention relates to new and useful improvements in a finger ring tensioner for knitting wool and the like and it consists in the combinations, constructions and arrangements of parts herein described and claimed.

More specifically, the invention proposes the construction of a finger ring tensioner characterized by the provision of a ring body for engagement upon a person's finger and carrying a top element provided with a passage of such construction that knitting wool or similar yarn may pass therethrough.

Still further it is proposed to mount a member upon said top element and extend the same across said passage for frictional engagement with said knitting wool against the base of the passage to tension the same when a person knits, darns, etc.

Still further it is proposed to provide a means mounted upon said top element and acting against said member and being adjustable in a manner to increase or decrease the pressure exerted by said member to control the tensioning of the knitting wool.

A further object of the invention is the provision of means for varying the frictional resistance of the base of the passage through which the knitting wool is passed to assist said means in controlling the tensioning of the knitting wool.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a hand showing a finger ring tensioner, according to this invention, in position upon the index finger.

Fig. 2 is an enlarged perspective view of the finger ring tensioner per se.

Fig. 3 is an edge elevational view of Fig. 2.

Fig. 4 is a perspective view of the clamp member per se.

Fig. 5 is a perspective view of the top element per se.

Fig. 6 is a vertical sectional view of the finger ring tensioner according to a modification of the invention.

Fig. 7 is an enlarged sectional view of a portion of a finger ring tensioner according to another modification of the invention.

Fig. 8 is a perspective view of the member for increasing the frictional resistance.

2

Fig. 9 is a perspective view of the bolt used for holding the member shown in Fig. 8.

Fig. 10 is a plan view of Fig. 5, with the wool passing thereover.

Fig. 11 is a sectional view of a portion of the tensioning means according to a modification thereof.

Referring more particularly to the drawing, the finger ring tensioner for knitting wool and the like, according to the invention, includes a ring body 10. This ring body is preferably constructed of wood, metal or plastic material. It is adapted to be engaged upon one's index finger, as shown in Fig. 1, and is formed with an oval shaped opening 10a to prevent unintentional turning of the same.

A top element in the form of a block 11 is formed upon one side of the ring body 10 and is provided with a passage 12 for knitting wool 13 illustrated by dot and dash lines in Fig. 2. The bottom ends 12a of the passage 12 are beveled to gradually increase the pressure on the wool and to prevent the wool from becoming entangled. This top element or block 11 is constructed of substantially the same material as the ring body 10 and may be formed integrally therewith or, if desired, the same may be separately constructed of a different material and secured to one side thereof.

30 A clamp member 14 is extended across the passage 12 and engages against the knitting wool 13 for frictionally engaging the wool against the base of the passage 12 for the purpose of tensioning the wool disposed between the top element 11 and the article being worked upon. This member 14 is in the form of a rectangular strip and is mounted within a second passage 15 formed in the top element or block 11 at right angles to the passage 12. The second passage 15 divides 35 off side lugs 15a which engage the sides of the member 14 retaining it against rotation relative to the block 11.

35 A means is mounted upon the top element or block 11 and acts against the member 14 for 40 resiliently urging the member against the knitting wool. This means comprises an upwardly extended stem 16 extending from the base of the passage 15. This stem 16 normally extends through an opening 16a formed in the member 14. The stem 16 is provided with threads 16a and 45 threadably carries a nut 17. A spring 18 is coaxially mounted upon the stem 16 and is disposed between the adjacent faces of the nut 17 and the member 14. When the nut 17 is turned to move 50 toward the member 14, the tension of the spring

18 will be increased and will cause the member 14 to engage against the knitting wool 13 with a greater amount of pressure to also cause the knitting wool to engage against the base of the passage 12 with a greater amount of pressure.

A washer 18^b may be placed over the stem 16, if desired. This washer will provide additional frictional opposition to the passage of yarn or the like through the device when the same is trained around the stem 13. It will be understood that the washer is to be loosely placed over the stem 16 so that a very minute amount of friction will be caused to be so opposed to the passage of the yarn.

The wool 13 may be placed under the member 14 and led through either side of the stem 16, depending upon the thickness of the wool and the amount of tension desired. If extremely thin wool is used, more tension may be applied by passing the wool in back of the stem 16, as illustrated in Fig. 10, thereby increasing the contact area with member 14 without changing the tension of the spring 18. In this condition a three point friction contact is produced, one at stem 16 and two at the passage 12.

The operation of this form of the invention is as follows:

The ring body 10 is engaged upon the knitting finger of the knitter's hand and the nut 17 is loosened, permitting the member 14 to be slightly disengaged from the passage 15 so that the knitting wool may be passed therebeneath and into the passage 12. The nut 17 is then properly adjusted to cause the member 14 to bear against the knitting wool with the desired amount of pressure to cause the same to be properly tensioned to meet the knitter's needs.

The knitting wool 13, after leaving the passage 12, will move to a position to be worked into the article being knitted. As the wool is used, it is merely necessary to draw more of the wool through the passage 12 to a position to be worked into the article being knitted.

In Fig. 6, the block 11 is shown as being removably mounted on the ring body 10 by means of a suitable bolt 11^a and nut 11^b so that the members 10 and 11 may be interchanged with corresponding members of any other size or color combination.

According to the modification of the invention shown in Figs. 7 to 9, inclusive, the construction of the finger ring tensioner is similar to that previously described except for the provision of a means for varying the frictional resistance of the base of the passage 12 through which the knitting wool 13 is passed. This is accomplished by mounting a disc-shaped element 19 in a recess 11^c of the block 11 immediately below the passage 12. A bolt 20 is passed through the top element 11 at right angles to the passage 12 and parallel to the passage 15 and directly below the center thereof. A means is provided for locking the disc-shaped element to the bolt 20 so that when the bolt is turned, the disc-shaped element will turn therewith. This means comprises an inwardly extended lug 19^a formed on the disc-shaped element 19. The lug 19^a engages a complementary longitudinal slot 20^a formed in the bolt 20. One end of the bolt 20 has a head 20^b provided with a knurled periphery for permitting the same to be conveniently gripped and turned. The outer end of the bolt 20 carries a nut 21 which is adapted to be manually tightened against the adjacent face of the top element for causing the head 20^b to frictionally engage the opposite face

of the top element 11 and hold the same against turning.

When the nut 21 is loosened, the head 20^b of the nut 21 may be conveniently gripped and turned for correspondingly turning the disc-shaped element 19.

The disc-shaped element 19, as shown in Fig. 8, is provided upon its peripheral edge with a plurality of flattened surfaces 19^b, preferably four in number. Each of these flattened surfaces is serrated and the serrations vary in roughness from the very fine to the very coarse. Thus, when the different flattened surfaces 19^b are brought into position at the base of the passage 12, the frictional resistance of the base wall upon the knitting wool will be varied to increase or decrease the tensioning thereof. In other respects, this form of the invention is similar to the previous form.

In Fig. 11 of the drawing, there is provided a nut 25 of generally smooth outer contour and formed with a threaded recess 36 into the end of which the threaded stem 16 threadedly extends. In this form of the invention, it will be apparent that there is less chance of possible catching of the knitting wool or the like by sharp edges of the protruding stem.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A finger ring tensioner for knitting wool and the like comprising a ring body for engaging on one's finger and having a top element with a passage for knitting wool, a member extending across said passage for frictionally engaging said knitting wool against the base of said passage, means mounted on said top element and acting against said member for resiliently urging said member against said knitting wool, and means for varying the frictional resistance of the base of said passage upon the passing of said knitting wool, said means comprising a bolt extending through said top element at right angles to said passage, a disc-shaped element mounted within an opening formed in said top element below said passage, means for locking said disc-shaped element to said bolt, means for holding said bolt against turning, said means being releasable to free said bolt so that the same may be turned to complementarily turn said disc-shaped element and bring different portions of its peripheral edge in position with the base of said passage, and a further means for varying the frictional resistance to the passage of the strand comprising a washer removably mounted upon the stem whereby the strand of knitting wool may be trained therearound to provide additional opposition to the passage of the strand.

2. A finger ring tensioner for knitting wool and the like comprising a ring body for engaging on one's finger and having a top element with a passage for knitting wool, a member extending across said passage for frictionally engaging said knitting wool against the base of said passage, means mounted on said top element and acting against said member for resiliently urging said member against said knitting wool, and means for varying the frictional resistance of the base of said pas-

sage upon the passing of said knitting wool, said means comprising a bolt extending through said top element at right angles to said passage, a disc-shaped element mounted within an opening formed in said top element below said passage, means for locking said disc-shaped element to said bolt, means for holding said bolt against turning, said means being releasable to free said bolt so that the same may be turned to complementarily turn said disc-shaped element and bring different portions of its peripheral edge in position with the base of said passage, a further means for varying the frictional resistance to the passage of the strand comprising a washer removably mounted upon the stem whereby the strand of knitting wool may be trained therearound to provide additional opposition to the passage of the strand, said disc-shaped element being formed with a plurality of flattened sides, each of which is serrated and varying in degree from fine to coarse.

3. A finger ring tensioner for knitting wool and the like comprising a ring body having an opening for engaging on one's finger, a top block element mounted on the top side of the ring body, said top block element being formed with a passage extended inwardly from the top face thereof and at right angles to the opening in said ring body and through which a strand of knitting wool is adapted to be extended, a member extending across said passage, a stem extending upwardly from said top block element and passing freely through an aligned opening formed in said member, a spring coaxially wound on said stem and engaging the top face of said member, a nut threadedly engaged on the top end of said stem and bearing against the top end of said spring, and a washer removably mounted upon the stem whereby the strand of knitting wool may be trained therearound to provide additional opposition to the passage of the wool.

4. A finger ring tensioner for knitting wool and the like comprising a ring body having an opening for engaging on one's finger, a top block element mounted on the top side of the ring body, said top block element being formed with a passage extended inwardly from the top face thereof and at right angles to the opening in said ring body and through which a strand of knitting wool is adapted to be extended, a member extending across said passage, a stem extending upwardly from said top block element and passing freely through an aligned opening formed in said member, a spring coaxially wound on said stem and engaging the top face of said member, a nut threadedly engaged on the top end of said stem and bearing against the top end of said spring, a washer removably mounted upon the stem whereby the strand of knitting wool may be trained therearound to provide additional opposition to the passage of the wool, and upwardly extending side lugs formed on said top block element and extending along the sides of said member holding said member against pivoting about said stem.

5. A finger ring tensioner for knitting wool and the like comprising a ring body having an opening for engaging on one's finger, a top block element mounted on the top side of the ring body, said top block element being formed with a passage extended inwardly from the top face thereof and at right angles to the opening in said ring body and through which a strand of knitting wool is adapted to be extended, a member extending across said passage, a stem extending upwardly

from said top block element and passing freely through an aligned opening formed in said member, a spring coaxially wound on said stem and engaging the top face of said member, a nut threadedly engaged on the top end of said stem and bearing against the top end of said spring, a washer removably mounted upon the stem whereby the strand of knitting wool may be trained therearound to provide additional opposition to the passage of the wool, and upwardly extending side lugs formed on said top block element and extending along the sides of said member holding said member against pivoting about said stem, said passage being extended through said side lugs at right angles thereto.

6. In a device of the character described, a block element having a passage formed and through which a strand of knitting wool or the like is adapted to be extended, a stem extending from said block element, a member mounted on said stem and extended across said passage and bearing resiliently against said knitting wool, and means for varying the frictional resistance of the base wall of said passage upon the passing of said knitting wool comprising a bolt extending through said block element at right angles to the passage and therebeneath, a disc-shaped element mounted on and locked to said bolt and located within an opening formed in said block element immediately below said passage, said disc-shaped element having flattened sides formed on different portions of its peripheral edge and each of which is selectively alignable with the base of said passage in several turned positions of said bolt, each of said flattened sides being serrated and varying in degree from fine to coarse, and a further means for varying the frictional resistance to the passage of the strand comprising a washer removably mounted upon said stem whereby the strand of knitting wool may be trained therearound to provide additional opposition to the passage of the wool.

7. In a device of the character described, a block element having a passage formed therein and through which a strand of knitting wool or the like is adapted to be extended, a member extended across said passage and bearing resiliently against said knitting wool, means for varying the frictional resistance of the base wall of said passage upon the passing of said knitting wool comprising a bolt extending through said block element at right angles to said passage and therebeneath, a disc-shaped element mounted on and locked to said bolt and located within an opening formed in said block element having flattened sides formed on different portions of its peripheral edge and each of which is selectively alignable with the base of said passage in several turned positions of said bolt, releasable means for holding said bolt against turning to prevent accidental turning of said disc-shaped element, and a further means for varying the frictional resistance to the passage of the strand comprising a washer removably mounted upon the stem whereby the strand of knitting wool may be trained therearound to provide additional opposition to the passage of said wool.

8. A finger ring tensioner for knitting wool and the like comprising a ring body having an opening for engaging on one's finger, a top block element mounted on the top side of the ring body, said top block element being formed with a passage extended inwardly from the top face thereof and at right angles to the opening in said ring body and through which a strand of knitting

wool is adapted to be extended, a member extending across said passage, a stem extending upwardly from said top block element and passing freely through an aligned opening formed in said member, a spring coaxially wound on said stem and engaging the top face of said member, a nut threadedly engaged on the top end of said stem and bearing against the top end of said spring, and a washer removably mounted upon the stem whereby the strand of knitting wool may be trained therearound to provide additional opposition to the passage of the wool, said nut being of smooth exterior surface and having its stem receiving opening extending but part way through the same.

9. In a device of the character described, a block element having a passage formed therein through which a strand of knitting wool or the like is adapted to be extended, a member extending across said passage and bearing resiliently against said knitting wool, means for varying the frictional resistance of the base wall of said passage upon the passing of said knitting wool comprising a bolt extending through said block element at right angles to said passage and therebeneath, a disc-shaped element mounted on and

locked to said bolt and located within an opening formed in said block element immediately below said passage, said disc-shaped element having flattened sides formed on different portions of its peripheral edge and each of which is selectively alignable with the base of said passage in several turned positions of said bolt, and a further means for varying the frictional resistance to the passage of the strand comprising a washer removably mounted upon the stem whereby the strand of knitting wool may be trained therearound to provide additional opposition to the passage of the wool.
